(57) CLAIM

The ornamental design for a hockey memorabilia display device, as shown and described.

DESCRIPTION

FIG. 1 is a right, front, perspective view of a hockey memorabilia display device showing my new design;

FIG. 2 is a top plan view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a bottom plan view thereof;

FIG. 8 is a right, rear, perspective view thereof; and,

FIG. 9 is a front elevational view thereof shown at a reduced scale and with an item of hockey memorabilia hanging therefrom.

The broken lines shown in the drawings illustrate portions of the hockey memorabilia display device that form no part of the claimed design.
